UNITED STATES PATENT OFFICE.

D'ORSAY McCALL WHITE, OF DETROIT, MICHIGAN, ASSIGNOR TO CADILLAC MOTOR CAR COMPANY, OF DETROIT, MICHIGAN, A CORPORATION OF MICHIGAN.

HYDROCARBON-MOTOR.

1,396,904.

Specification of Letters Patent. Patented Nov. 15, 1921.

Application filed November 24, 1916. Serial No. 133,186.

To all whom it may concern:

Be it known that I, D'ORSAY McCALL WHITE, a loyal subject of the King of England, and resident of Detroit, Wayne county, 5 State of Michigan, have invented certain new and useful Improvements in Hydrocarbon-Motors, of which the following is a specification.

This invention relates to hydrocarbon motors, and particularly to cylinder jacket constructions therefor.

One of the objects of this invention is to provide an improved disposition and arrangement of the motor cylinder gas passages.

Another object of this invention is to provide improved means for efficiently heating and vaporizing hydrocarbon fuels, and for conducting and distributing the gaseous mixture to the cylinder combustion chamber.

Another object of this invention is to provide a V motor having its cylinder intake and exhaust passages so arranged that various parts of the motor, such as the valves and other driving mechanism are rendered very accessible thus providing for easy examination, assembling and disassembling of these parts.

Another object of this invention is to provide an arrangement of motor gas passages which permits the utilization of the heat of exhaust gases for vaporizing the fuel, and which also utilizes the cylinder cooling medium for qualifying the heating effect of said gases on said fuel.

These, and other objects, will clearly appear from the following description, taken in connection with the accompanying drawings, which form a part of this specification, 40 and in which:

Figure 1 is an end view, with portions in section, of a hydrocarbon motor power plant, embodying a form of this invention;

Fig. 2 is a vertical section substantially on the line 2—2 of Fig. 3;

Fig. 3 is a longitudinal transverse section substantially on the line 3—3 of Fig. 2 and Fig. 5;

Fig. 4 is a longitudinal transverse section substantially on the line 4—4 of Fig. 5; and,

Fig. 5 is a vertical longitudinal section substantially on the line 5—5 of Fig. 4.

Referring to the drawings, 10 illustrates a crank case, in bearings of which may be 55 suitably mounted a crank shaft 11 and a

cam shaft 12. A plurality of cylinder blocks 13 and 14, respectively, may be arranged in V relation on the crank case 10 and secured thereto as by bolts 15. Each block comprises a plurality of cylinders 16, surrounded by an integral jacket 17. Each cylinder has formed in its inner face a valve intake port 18, and an exhaust valve port 19, adapted to be controlled by well known puppet valve mechanisms 20. The valve mechanisms are adapted to be operated in any well known manner from the cam shaft 12 within the crank case 10.

A gas intake or distributing passage 21, is cored out of a conduit 22, formed integral 70 with, and arranged within, the jacket 17. The intake 21 is provided with a port 23 at the inner face of the cylinder block and has ports leading to valve chambers 24. A T shaped conduit and carbureter 23', may be 75 arranged between the blocks 13 and 14, with its outlets suitably connected to the inlet ports 23.

An exhaust passage 25 is also formed in the conduit 22 below the intake passage 21, 80 with only a comparatively thin longitudinally extending dividing wall 26 therebetween. The exhaust passage 25 is in constant communication with cylinder exhaust valve chamber ports 19, and is provided with 85 an outlet branch 27 formed intermediate the ends of the blocks 13 and 14, and extending transversely thereof from the jacket inner face to the other face where the gases may be discharged exteriorly of the cylinder block 90 through a port 28.

Exhaust pipes 29 may be suitably secured in position along the outside of the block in communication with the ports 28. It will be noted that with the foregoing arrangements, 95 the incoming gases are adapted to be distributed to the various cylinders after flowing through the passage 21, the bottom of which is formed by a dividing wall 26 below which the exhaust gases are discharged from 100 the cylinders, with the result that the heat of the outgoing exhaust gases will be imparted to and insure the vaporization of the hydrocarbon fuel passing through the intake. If any of the heavier hydrocarbon 105 fuel elements are precipitated or condensed within the gas intake passage 21, the heat of the dividing wall 26 will tend to immediately volatilize these elements.

Where it has been attempted heretofore, 110

to utilize the heat of the exhaust gases for improving the vaporization of the hydro-carbon fuel, considerable difficulty has been experienced, on account of the decrease in 5 volumetric efficiency, and the falling off in power, of the motor caused by the undue expansion of the incoming charge of gas, which, of course, results in diminishing the weight of each charge. These difficulties 10 have been overcome, in this invention, by so arranging the intake and exhaust passages that the heating effect of the exhaust gases on the fuel mixture is qualified by the temperature of the surrounding cooling 15 medium within the jacket. In other words, assuming that the exhaust gases have radiated sufficient heat through the dividing wall 26, to vaporize the previously condensed hydrocarbon fuel within the intake 20 passage 21, the surrounding cooling medium within the jacket 17 will also maintain the temperature of the incoming charge below the desired limit.

It is to be also noted that by my improved 25 means for conducting the exhaust gases from the inner to the outer faces of the blocks of a V type motor, and arranging the exhaust pipe along the outer face, the space between the inner faces of the blocks is left 30 entirely free and unobstructed, save for the carburetor and intake, which may be easily removed. By removing the carburetor and intake, the space between the cylinder blocks will be entirely free from obstructions, thus 35 permitting very easy adjustment and disassembly of the various valve mechanisms and their driving parts.

It will be understood, of course, that various modifications and changes will occur to 40 those skilled in the art, without departing from the spirit and scope hereof.

Having thus described my invention, what I claim and desire to secure by Letters Patent is:

45 1. In an internal combustion engine, a multicylinder block having a cooling liquid jacket, and a combined intake and exhaust conduit inclosed within said jacket and having a common dividing wall between its passages; said conduit having centrally arranged inlet and outlet openings upon opposite sides of said block.

50 2. In an internal combustion engine, a multi-cylinder block having a cooling liquid jacket, and a plurality of cylinder intake and exhaust ports respectively formed therein, and a conduit arranged within said jacket and divided by a common wall into intake and exhaust passages; said passages communicating with said intake and exhaust ports, respectively, and having inlet and outlet openings centrally arranged in respect thereto and upon opposite sides of said cylinder block.

55 3. In an internal combustion engine, a

block having a plurality of cylinders each provided with an intake port and an exhaust port, and a cooling liquid jacket common to all of said cylinders; and a conduit surrounded by said jacket and having a longitudinally extending dividing wall forming passages above and below said wall, the passage above said wall being connected with each of said intake ports, and the passage below said wall being connected with each 75 of said exhaust ports.

4. In an internal combustion engine, a block of cylinders having intake and exhaust ports formed at one side thereof, and which block has a cooling liquid jacket common to 80 all of said cylinders, said jacket having two passages arranged therein and separated by a common wall; one of said passages being adapted to conduct exhaust gases from said exhaust ports through said jacket and to discharge said gases at a point exteriorly of said jacket and centrally of the length of said block, and at the side thereof opposite said ports, and the other of said passages being in communication at its central portion 90 with suitable mixture supply means and adapted to conduct combustible mixture from a point exteriorly of said jacket and at the same side thereof as said ports through said jacket and to said inlet ports. 95

5. In an internal combustion engine, two cylinder blocks arranged in V-relation and having each a plurality of cylinders, a cooling liquid jacket common to all the cylinders of the block, and an inlet and an exhaust 100 port for each cylinder of the block in question; valves for controlling said several ports; intake and exhaust passages located within and extending along the jacket of each cylinder block and communicating, respectively, with the inlet and exhaust ports of said block, and which passages are separated from one another by a wall common to both said passages; combustible mixture supplying means located between said cylinder blocks and adapted to supply combustible mixture to both the intake passages aforesaid through ports located upon the inner sides of said blocks and communicating with said passages; and exhaust conduits 110 leading from said exhaust passages and discharging therefrom through ports located upon the outer sides of said blocks, and at a level below the level of the ports through which combustible mixture is supplied to 115 said intake passages.

6. In an internal combustion engine, two cylinder blocks arranged in V-relation and having each a plurality of cylinders, a cooling liquid jacket common to all the cylinders 125 of the block, and an inlet and an exhaust port for each cylinder of the block in question; valves for controlling said several ports; intake and exhaust passages located within and extending along the jacket of 130

each cylinder block and which passages are separated from one another by a wall common to both said passages, said passages being arranged upon the inner sides of said blocks, and the same communicating, respectively, with the inlet and exhaust ports of the said blocks; combustible mixture supplying means located between said cylinder blocks communicating with said inlet passages adjacent the middle portions thereof and adapted to supply combustible mixture to both the intake passages aforesaid; and exhaust conduits leading from said exhaust passages, respectively, to the outer sides of said cylinder blocks and discharging at said outer sides centrally of the length of said blocks.

7. In an internal combustion engine, two cylinder blocks arranged in V-relation and having each a plurality of cylinders, a cooling liquid jacket common to all the cylinders of the block, and an inlet and an exhaust port for each cylinder of the block in question, valves for controlling said several ports; intake and exhaust passages located within and

extending along the jacket of each cylinder block and communicating, respectively, with the inlet and exhaust ports of said block, and which passages are separated from one another by a wall common to both said passages, said passages being arranged upon the inner adjacent sides of said cylinder blocks and the upper of said passages being the inlet passage which communicates with the intake ports of the cylinder block in question; combustible mixture supplying means located between said cylinder blocks and adapted to supply combustible mixture to both the intake passages aforesaid through ports communicating with said passages and which ports are centrally disposed relative to the length of said blocks; and two exhaust conduits leading one from each of said exhaust passages and discharging through ports which are centrally located relative to said blocks, and which are upon the sides of said blocks opposite said inlet ports.

In testimony whereof I affix my signature.

D. McCALL WHITE.
